UNITED STATES PATENT OFFICE.

HENRY BRADFORD AND HOMER V. PARIS, OF CAVE SPRING, GEORGIA.

RECORDING DEVICE.

No. 911,435.

Specification of Letters Patent.

Patented Feb. 2, 1909.

Application filed October 23, 1907. Serial No. 398,834.

To all whom it may concern:

Be it known that we, HENRY BRADFORD and HOMER V. PARIS, citizens of the United States, residing at Cave Spring, in the county of Floyd and State of Georgia, have invented 5 new and useful Improvements in Recording Devices, of which the following is a specification.

This invention relates to recording devices 10 for steam boilers, and one of the principal objects of the same is to provide simple and efficient means for recording the steam pressure in a boiler at every hour throughout the day and night.

Another object of the invention is to provide 15 a steam gage and time piece connected by mechanism for recording at each hour upon a removable disk the steam pressure of the boiler at each hour.

These and other objects may be attained 20 by means of the construction illustrated in the accompanying drawings in which—

Figure 1 is a front elevation of a recording device made in accordance with our invention. 25 Fig. 2 is a side elevation and partial section of the same. Fig. 3 is a rear elevation showing the mechanism in one position. Fig. 4 is a similar view showing the mechanism in the position which it assumes in recording the 30 steam pressure upon the hour. Fig. 5 is a face view of a record disk with a record thereon, such as the recording device is adapted to make.

Referring to the drawings for a more specific 35 description of our invention the numeral 1 designates a base or support for the mechanism and 2 is an ordinary alarm clock or time piece supported in an opening in the base 1 while 3 is an ordinary steam gage also supported in the base 1 below the time piece 40 2. A steam pipe 4 establishes communication between the boiler and steam gage. The steam gage is provided with the ordinary dial 5 and a hand or pointer 6 to indicate the pressure 45 of steam upon the dial.

Referring to Figs. 2, 3 and 4 a cam 7 fixed to the minute hand arbor 8 of the time piece at the back of the clock is arranged to rotate in contact with a roller 9 mounted upon the 50 upper end of a sliding rod 10 fitted in a guide 11 secured at the back of the clock and provided with lugs 12 through which the rod 10 freely passes. Below the guide 11 the rod 10 is bent outwardly at right angles as at 13 and 55 upon said angular portion a downwardly extending finger 14 is provided. From the an-

gular portion 13 the rod 10 is bent again at right angles to form the vertical member 15 which is mounted to slide in guides 16 and 17 secured to the rear side of the gage. Secured 60 to the base 1 in rear of the steam gage 3 is a supporting plate 18, said plate being connected to the base 1 by means of suitable screws 19. The arbor 20 upon which the indicator hand 6 is mounted extends through the plate 18 and connected to the outer end 65 of said arbor to rotate therewith is a disk 21, said disk being provided with a series of points or prongs 22. Rigidly secured to the plate 18 is a ring 23, said ring being secured 70 to said plate by means of countersunk screws 24. The ring 23 is provided with a rabbeted periphery and fitted in the rabbet to rotate therein is a ratchet disk 25, said disk having a series of peripheral ratchet teeth 26 75 and upon the face of said disk is produced the hour indicating numerals 27 from 1 to 12, as shown more particularly in Figs. 3 and 4.

Connected to the lower end of the vertical member 15 of the sliding rod 10 is a spring 80 28, said spring being connected to a keeper 29 on the plate 18 while the free end of said spring is provided with a perforation through which the member 15 passes and a nut 30 fitted to the end of the member 15 holds said spring in place. Carried by the member 15 85 is a pawl 31 which engages the peripheral teeth 26 of the disk 25. A hammer 32 provided with a long shank 33 connected to a pintle 34 is actuated by the sliding rod as will 90 presently appear. The pintle 34 is journaled at its opposite ends in a bearing plate 35 provided with lugs 36 in which said pintle 34 is journaled. A spring 37 secured to the pintle 34 and to the bearing 35 exerts its 95 tension to normally hold the hammer 32 outward away from the back of the gage as shown in Fig. 2. A spring pawl 38 is secured to the bearing 35, said pawl engaging the teeth 26 to prevent the backward rotation of 100 the disk 25. Upon one end of the pintle 34 is an angular enlargement 39 disposed in the path of the finger 14. A paper disk 40 having printed thereon the same indicating numbers as are on the dial 5 of the gage is 105 connected to the points 22 and a disk of carbon paper 41 is also secured under the disk 40 upon said points 22. The printed numbers on the disk 40 are disposed in the same relative position as the numbers on the dial 5. 110

The operation of our invention may be briefly described as follows: As the minute

hand arbor 8 of the time piece rotates the cam 7 raises the rod 10 against the tension of the spring 21 and as the cam 7 arrives at the position shown in Fig. 4 which is upon 5 an hour the roller 9 is released from the cam and the spring 28 pulls the rod 10 downward until the finger 14 strikes the enlargement 39 on the pintle 34 which actuates the hammer 32 to strike the paper disk 40 immediately 10 over the corresponding hour on the disk 25. The hour indicators 27 being raised from the disk 25 will be printed on the inner side of the paper disk 40. Since the disk 40 is carried by the arbor 20 of the indicator hand 6 15 the hour will be printed upon the disk 40 in line with the figures which indicate the steam pressure at that moment. As the cam 7 makes a complete revolution in one hour it will be obvious that the hammer 32 is actuated at each hour to impress the hour upon 20 the under side of the paper disk 40 at one side of or near the figures which indicate the steam pressure at the time the hour is printed.

25 From the foregoing it will be obvious that a recording device made in accordance with our invention will indicate upon a paper disk the steam pressure in the boiler at each hour of the day and night. It will be understood 30 that the disks 40 are to be replaced by new disks containing only the figures of the steam pressure dial at stated intervals.

Having thus fully described the invention what is claimed as new is:

35 1. A recording device, comprising a time piece, a steam gage, a ratchet disk mounted

to rotate at the back of said steam disk and having raised figures to indicate the hours, a disk connected to the arbor of the indicator hand of the gage, means for connecting a 40 paper disk to said first named disk, a cam connected to the minute hand arbor of the time piece, a sliding rod actuated by said cam, and means for rotating the ratchet disk and registering upon the paper disk each hour 45 the steam pressure indicated by the gage.

2. In a recording device, the combination of a time piece, a steam pressure indicator, a cam on the minute arbor of the time piece, a sliding rod, a pawl carried by the rod, a 50 ratchet disk having the hours indicated thereon, a disk connected to the arbor of the pressure indicator hand, said disk provided with points or prongs, a paper disk provided with a printed indicator dial there- 55 on secured to said points or prongs, and means carried by the sliding rod for registering upon the paper disk each hour the pressure indicated by the pressure gage.

3. In a device of the character described, 60 the combination of a time piece, a steam pressure indicator, and connected mechanism comprising a cam, a sliding rod, a pawl, and a printing hammer for recording upon a paper disk the steam pressure at each hour. 65

In testimony whereof we affix our signatures in presence of two witnesses.

HENRY BRADFORD.
HOMER V. PARIS.
